UNITED STATES PATENT OFFICE.

HENRY R. SMITH, OF GAMBRILLS, MARYLAND, ASSIGNOR OF ONE-THIRD TO ASA A. JOYCE AND ONE-THIRD TO LUTHER H. GADD, OF ANNAPOLIS, MARYLAND.

WRENCH.

No. 821,488.

Specification of Letters Patent.

Patented May 22, 1906.

Application filed September 25, 1905. Serial No. 280,022.

To all whom it may concern:

Be it known that I, HENRY R. SMITH, a citizen of the United States, residing at Gambrills, in the county of Anne Arundel and State of Maryland, have invented certain new and useful Improvements in Wrenches; and I do declare the following to be a full, clear, and exact description of the invention, such as will enable others skilled in the art to which it appertains to make and use the same.

This invention relates to improvements in wrenches.

The object of the invention is to provide a wrench which will be simple, strong, and durable in construction, efficient in operation, the sliding jaw of which may be quickly and easily adjusted and firmly held in its adjusted position.

With the above and other objects in view the invention consists of certain novel features of construction, combination, and arrangement of parts, as will be hereinafter described and claimed.

In the accompanying drawings, Figure 1 is a side view of a wrench constructed in accordance with the invention. Fig. 2 is an edge view of the same, and Fig. 3 is a longitudinal sectional view.

Referring more particularly to the drawings, 1 denotes the wrench, which consists of a stationary jaw 2, having a shank or stem 3, a movable or sliding jaw 4, having a stem or shank 5, and an integral handle 6, the inner side of said handle 6 being curved outwardly toward its outer end, as shown. The stem of the sliding jaw is also provided with a longitudinally-disposed slot 7, through which is adapted to project a post 8, which

is pivotally secured to the stationary jaw-shank 3 and projects laterally and at right angles from the inner side of said shank. On the outer projecting end of the post 8 is formed a pawl or dog 9, the inner face of which is preferably serrated or provided with teeth 10, adapted to engage the serrated or toothed outer side of the movable-jaw shank 5 when the latter is brought into engagement therewith, thus holding said movable jaw and shank in their adjusted position.

On the inner end of the stationary-jaw shank is secured a lateral right-angularly-

projecting bail-shaped guide 12, through the outer portion of which the handle end of the movable-jaw shank is adapted to slide. Pivotedly mounted in the bail-shaped guide 12 between the movable-jaw shank and the inner end of the stationary-jaw shank is an operating-handle 13, said handle being provided on its inner face adjacent to the pivotal end thereof with a cam-shaped projection 14, which is adapted to bear against the inner side of the handle end of the movable-jaw shank, whereby when the handles 6 and 13 are gripped the shank of the movable jaw 65 will be forced outwardly into engagement with the pawl or dog 9, thereby holding said movable jaw in its adjusted position.

In using the wrench the stationary jaw is engaged with the nut or other device, after which the movable jaw and shank are slipped outwardly into engagement with said nut, and after being so engaged the handle 6 of said movable jaw and the pivoted handle 13 are gripped, which will cause the teeth on the outer side of the sliding-jaw shank to engage the teeth on the inner side of the pawl or dog, thus holding said movable jaw in firm engagement with the nut. When it is desired to readjust the movable jaw, the pivoted handle 13 is released, so that the cam 14 thereon will be disengaged from the movable-jaw shank, thus allowing the same to be disengaged from the teeth of the pawl or dog 9, after which the shank may be slipped backward or forward in the bail-shaped guide 12, thereby moving the jaw 4 to the desired position.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In a wrench, the combination with the stationary jaw and shank, of a movable jaw and shank, handles arranged on said shanks,

a locking-dog 9 pivoted on said stationary-jaw shank, and means operated by the gripping of the wrench-handles to engage the shank of said movable jaw with said locking device, thereby holding said movable jaw in its adjusted position, substantially as described.

2. In a wrench, the combination with a stationary jaw and shank, of a movable jaw and shank, said movable-jaw shank having formed therein a longitudinally-disposed slot, a locking pawl or dog pivotally mounted in said stationary-jaw shank and adapted to project through the slot in said movable-jaw shank, handles arranged on the inner ends of said jaw-shanks, and means operated by the gripping of said handles to engage said movable-jaw shank with said locking pawl or dog, substantially as described.

20 3. In a wrench, the combination with a stationary jaw and shank, of a movable jaw and shank, said movable-jaw shank having formed therein a longitudinally-disposed slot, a locking pawl or dog pivotally mounted in said stationary-jaw shank and adapted to project through the slot in said movable-jaw shank, a guide arranged on the inner end of said stationary-jaw shank, a rigid handle formed on said movable shank, a movable handle pivoted in said guide, and means whereby the gripping of said handles will en-

gage said movable-jaw shank with said locking pawl or dog, substantially as described.

4. In a wrench, the combination with a stationary jaw and shank, of a movable jaw and shank, said movable-jaw shank having formed therein a longitudinally-disposed slot, teeth or serrations formed on the outer side of said shank, a post pivotally mounted in said stationary-jaw shank, and adapted to project through the slot in said movable-jaw shank, a pawl or dog arranged on the projecting end of said post, teeth formed on the inner side of said pawl to engage the teeth on said movable-jaw shank, a bail-shaped guide arranged on the inner end of said stationary-jaw shank, a rigid handle formed on said movable-jaw shank, a movable handle pivotally mounted in said bail-shaped guide and a cam formed on said movable handle to engage said movable-jaw shank whereby when said handles are gripped said movable-jaw shank will be engaged with said locking-pawl, substantially as described.

In testimony whereof I have hereunto set my hand in presence of two subscribing witnesses.

HENRY R. SMITH.
